UNITED STATES PATENT OFFICE

GUILLAUME BUSSON, OF NEUILLY-SUR-SEINE, FRANCE

DESIGN FOR A COMBINED AUTOMOBILE BODY AND FENDERS

Application filed November 8, 1929, Serial No. 33,380, and in Great Britain July 12, 1929. Term of patent 7 years.

To all whom it may concern:

Be it known that I, GUILLAUME BUSSON, a citizen of the French Republic, residing at Neuilly-sur-Seine, Seine, France, have invented a new, original, and ornamental Design for Combined Automobile Body and Fenders, of which the following is a specification, reference being had to the accompanying drawings, forming part thereof.

Figure 1 is an elevational view of an automobile, showing my new design.

Figure 2 is a top plan view of the same.

Figure 3 is a front view of the same.

Figure 4 is a rear view of the same.

I claim:

The ornamental design for a combined automobile body and fenders, as shown.

GUILLAUME BUSSON.
